CLAIM

The ornamental design for a catheter imaging light source, as shown and described.

DESCRIPTION

FIG. 1 is a perspective view of a catheter imaging light source showing our new design;

FIG. 2 is one side plan view thereof;

FIG. 3 is a side elevational view thereof;

FIG. 4 is a back plan view thereof;

FIG. 5 is a side elevational view thereof opposite that shown in FIG. 3; and,

FIG. 6 is a bottom plan view thereof.

FIG. 1.

FIG. 2.

FIG. 3.

FIG. 4.

FIG. 5.

FIG. 6.
